US00D358369S

United States Patent [19]

Shimizu et al.

[11] Patent Number: Des. 358,369

[45] Date of Patent: ** May 16, 1995

[54] PROGRAM SET CONTROLLER

- [75] Inventors: **Norio Shimizu; Yuichi Watanabe**,
both of Tokyo, Japan
- [73] Assignee: **Koyo Electronics Industries Co., Ltd.**,
Tokyo, Japan
- [**] Term: **14 Years**
- [21] Appl. No.: **11,084**
- [22] Filed: **Jul. 26, 1993**

[30] Foreign Application Priority Data

- Jan. 29, 1993 [JP] Japan 5-2393
- [52] U.S. Cl. **D13/164**
- [58] Field of Search D13/162, 164;
364/DIG. 2, 926.9, 949; 361/686

[57] CLAIM

The ornamental design for a program set controller, as shown.

DESCRIPTION

FIG. 1 is a front, top and right side perspective view of a program set controller showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a rear, bottom and left side perspective view thereof.

FIG. 2

FIG. 3

*FIG. 4**FIG. 5*FIG. 6

FIG. 7

FIG. 8
